UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

1,419,635.

Specification of Letters Patent. Patented June 13, 1922.

Original application filed March 14, 1917, Serial No. 154,650. Divided and this application filed June 20, 1918. Serial No. 240,980.

To all whom it may concern:

Be it known that I, ALFRED G. F. KUROWSKI, a citizen of the United States, formerly a citizen of Germany, residing in Brooklyn 5 borough, in the county of Kings, city and State of New York, have invented certain new and useful Improvements in Typewriting Machines, of which the following is a specification.

10 My invention relates to typewriting machines, and is herein disclosed as applied to tally-strip devices on an Underwood standard typewriter. Such devices are usually used for preserving a tally-strip record of 15 items on sales sheets, bills, etc., and usually include a holder both for the tally-strip itself and for the carbon paper which makes the duplicate record thereon of the original on the bill or sales sheet. Such devices therefore 20 are advantageously constructed, so as to feed the tally-strip along at each operation of the line-space mechanism; but for the purpose of making a condensed record, the feeding of the tally-strip is advantageously 25 the minimum line-space, whereas the line-spacing of the original work-sheet is often considerably larger, to enable the bill or sales sheet to present an agreeable appearance.

30 This present invention relates specifically to mechanism including a plurality of rolls for supporting the tally-strip and carbon paper holding device above referred to, and to subordinate parts and auxiliary features 35 of the tally-strip supporting device, this present invention being divided out of my co-pending application, Serial No. 154,650, filed March 14, 1917 (now Patent No. 1,302,676, dated May 6, 1919).

40 The object of my invention is to provide an improved mechanism including a plurality of rolls for supporting the tally-strip and the carbon-strip used in conjunction therewith, all as will hereinafter and at 45 length appear.

My invention is illustrated in its preferred embodiment in the drawings accompanying and forming a part of this specification, although it will be appreciated that the same 50 may be embodied in other forms, not illustrated, and that my invention includes all such variations and modifications of the particular tally-strip supporting mechanism

illustrated, and hereinafter described and claimed, as come within the scope of the concluding claims wherein the particular features in which my invention consists are pointed out.

Other features and advantages will hereinafter appear.

In the accompanying drawings,

Figure 1 is a perspective view showing my invention as applied to the carriage of an Underwood typewriting machine.

Figure 2 is a sectional view showing a 65 clamp for catching the leading end of the tally-strip and securing it to the roll upon which it is wound.

Figure 3 is a fragmentary view also illustrating the holding mechanism shown in 70 Figure 2.

Figure 4 is a sectional view showing the roll-supporting device upon a plane extending longitudinally of the typewriter platen, and upon a larger scale than it is shown in 75 Figure 1.

Figure 5 is a perspective view showing the means for fastening the mandrel or spindle of the tally-strip roll in place.

Figure 6 is an end view of the fastening 80 means shown in Figure 5.

Figure 7 is a fragmentary view showing a detail of the carbon-paper-roll support.

In the usual Underwood typewriter carriage the platen 1 is fast upon a supporting 85 shaft which is journaled in the end plates 3, 4 of the platen frame of the typewriter carriage, which shaft is provided at its ends with knobs, one of which is shown at 5, whereby it may be rotated.

The typewriter carriage includes the usual auxiliary features for holding the paper in place upon the platen, and for advancing the platen, the latter mechanism including a line-spacing lever 15 through which the line-spacing mechanism is operated to advance the platen, as will be appreciated.

At the right-hand end of the carriage is located a tally-strip device which includes a pointed spindle 24, on which is mounted a 100 roll of paper 25 adapted to be used as a tally-strip. The free end this paper is carried down across the paper table 13 beneath the platen and up in front of the platen until its leading edge reaches a winding roll 105 26, said roll comprising a spring 27 under

which the leading edge of said strip 25 may be caught.

The part 28 of the platen around which the tally-strip 25 passes is free to turn upon the platen shaft whereby the platen is supported from the end plates 3, 4, thus allowing the section 28 to turn freely upon said shaft, motion being transmitted thereto by the tally-strip web 25 acting as a belt and 10 the section 28 serving as an abutment or support for the tally-strip at the point at which the type-bars of the machine engage the same.

In order to drive the tally-strip as the line-spacing mechanism is operated, the roll 26 is adapted to be driven from and by the line-spacing mechanism, said roll for this purpose being fast upon a shaft 29, which is journaled in the ends of the side pieces 30 and 31 of the roll-supporting frame. Adjacent the outer end of the shaft 29, there is secured fast thereto a ratchet wheel 32, which ratchet wheel is adapted to be engaged by a pawl 33 to thereby advance the shaft 29 and wind the tally and carbon sheets thereon. The pawl 33 is operated from the line-spacing mechanism at the left-hand end of the carriage, motion being transmitted to said pawl through a long rock-shaft 34 supported in bearings carried by the carriage. The mechanism, however, through which motion is transmitted from the line-spacing mechanism to the pawl 33 and ratchet wheel 32 is not illustrated in detail 35 in this present application, as the same is in no way involved herein. Such mechanism is, however, illustrated and described at length in my patent, above referred to.

The mandrel or spindle 24, on which the paper or tally-strip roll 25 is carried, is adapted to be thrust in through the wall 31 of the tally-strip device through the center of the roll 25, and is long enough to extend beyond the wall 30, in which position it 45 thrusts aside a latch or catch 74 in the form of a slide. This catch (Figures 4, 5 and 6) has two sides 75 and 76 cut out at 77, so that where cut out at 77, the mandrel 24 may enter between the two sides 75 and 76. 50 The slide 74 has a turned-over end 78 by which it is adapted to be pressed down against the tension of a spring 70, which normally holds the catch 74 in its upper position. The catch 74 is guided by its two 55 sides 75 and 76 in a hood 80 having tenons 82, which engage and align within slots cut in the wall 30, said tenons also carrying a bushing 83, which extends within and beyond the wall 30 and serves as a journal for 60 the mandrel 24. In order to hold the mandrel 24 at the proper place, the sides 75 and 76 of the catch 74 engage in a circular slot 84 cut in the surface of the mandrel 24 and in which the sides 75 and 76 seat themselves 65 when the catch 74 is lifted upward

by its spring 70. The knurled right-hand extension 85 of the mandrel 24 is large enough to prevent the mandrel from slipping too far when inserted into the opening 86 in the wall 31 in which it is journaled. 70

In order to make it impossible for the tally-strip paper roll 25 to be wrongly placed on the mandrel 24, said roll 25 has a spool or core 87, which extends entirely out to one end 88 of the tally-strip or paper roll while cut away and terminating short of the opposite end thereof. When the roll is to be inserted in the tally-strip device, an end plate 89, having a bushing 90 extending inwardly therefrom and adapted to complete the core for the roll 25, is inserted in the roll, and then the roll is inserted between the walls 30 and 31, with its end 88, together with the adjacent end of the core 87, bearing against a spider spring projection 91 which is adapted to hold the roll tightly when the roll is inserted so that the core or roller 87 bears against the margin of the opening in the spider. When thus inserted, the end of the bushing 90 bears against the adjacent end of the core 87, and a hub in the form of a boss 93 on the end plate 89 bears against the wall 31. The mandrel passes through the end plate 89, the core 87, the opening in the spider 91, and out until it engages and is caught by the catch 74. The spider 91 has its outlying spring ends bent S-shaped to catch in openings in an end plate 94 which has a hub in the form of a boss 95, said hub adapted to engage the boss-bushing 83 and to be fastened thereto by a set screw 96. 90 95 100

The winding roll 26 may include a wooden body 97, which is held by a set screw 98 to 105 its shaft 29. Said shaft is journaled in the end walls 30 and 31, and to hold it in position, it is provided with a shoulder 99 bearing against the inside of the end wall 30, and it is also provided with a collar 100 outside the end wall and lying closely against said wall, said collar being held to the shaft 29 by a set screw 101. In order to provide friction to prevent the winding roll 26 from turning too easily, a spider friction spring 115 102 bears against the inside of the wall 30, and the outlying arms thereof bear against the flange 103 of said winding roll 26.

In order to make it easy to catch the end of a tally-strip on said winding roll, the 120 spring catch 27 lies in an axial slot 104 on said roll, and said spring is hinged at the opposite side of said roll at 105 (Figures 2 and 3), with the result that the arc-shaped portions of the spring extending around to 125 the hinge point furnish sufficient springiness to hold the main part of the spring in its slot 104, to thereby clamp the leading edge of the tally-strip. In order to make it easy to raise the spring catch, a finger-hole 107 is 130

cut out of the winding roll. The carbon paper used with these tally-strips is often in the form of a single rolled strip or web having two colors. In order to make sure that 5 the typist shall insert this rolled strip or carbon-web roll 107^a correctly on its pointed mandrel or spindle shaft 108, it is provided with a spool or core which extends entirely out to the left-hand side 110 thereof, and 10 also entirely out to the right-hand side 111. This core or roller, in the illustrated embodiment of the invention, comprises wooden end plugs 109 connected together by an outer shell 109^a which may be of metal. The 15 right-hand end plug 109 is axially recessed or apertured to receive the inwardly-extending hub or bushing 111^a of a flange plate 112, and for this purpose, the wooden core end 109 at the right is provided in its 20 outer end with two end recesses or openings 113, either one of which may engage a pin 114 which projects endwardly inward from the face of the flange 112 for the purpose of entering one or the other of the holes 113, 25 thus compelling the flange to revolve with the roll 107^a and its core.

Said flange plate 112 is provided with an outwardly-extending hub or boss 115 which bears against the plate 31 and which also 30 forms the support for a detent 116 which is adapted to lock the flange plate 112 to the mandrel 108, so that the two revolve together. The detent 116 (Figures 4 and 7) is seated in a bore 117, and is pressed inwardly 35 by a spring 118, so that when in the proper position, said detent is adapted to enter into a longitudinal slot kerf 119 in the mandrel 108, and when thus seated, the mandrel and the flange turn as a unit. The spring 118 40 encircles the hub 115 and is held in place by a pin 120, which extends across a cut-away segment of the hub 115.

The outer end of the mandrel 108 has suitably attached thereto a crank handle 45 121, for the re-winding of a carbon-roll, and by which it may revolve and the adjustments are such that when a carbon roll is in position on the mandrel 108, the turning of the handle 121 will cause the detent 116 to seat 50 itself so that the carbon roll will turn with the handle.

The end 110 of the carbon roll, together with the left-hand end plug 109, bears 55 against a spider spring 122, which may be substantially like the spring 91, and bears against a flange plate 123, which is mounted like the plate 94 on a hub 124, and held by a set screw 125 to the internal extension of a hub or bushing 126. This hub includes a 60 latch 127 like the latch 74 and the other parts may be substantially identical so that the mandrel 108 may be released from the latch 127 which normally holds it by depressing the upper end of the latch. When 65 the carbon-web roll 107^a is inserted its end

111, the adjacent end of the shell 109^a and the recessed outer end of the right-hand core plug 109 all bear against the flange plate 112.

While the paper roll 25 and the carbon 70 roll turn freely on their shaft or mandrel, the winding roll 26 is fast to the shaft by the set screw 98.

The inner hub or bushing 111^a for the carbon-web roll 107^a is not adapted to be 75 received by the tally-strip paper roll 25 having the core 87, by reason of the fact that the bushing 111^a projects too far; and the bushing 90 for the tally-strip roll 25 is not adapted to be received by the right-hand 80 core plug 109 of the carbon-web roll 107^a, by reason of being of too small a diameter. Also, in the construction shown in the drawings, the projecting pin 114 would prevent the spool end or flange plate 112 from being 85 applied to the tally-strip roll 25.

The frame which comprises the side pieces 30 and 31 supporting the roll 26, etc., is adapted to be swung either into a nearly upright position, which is the normal position shown in full lines in Figure 1, or thrown down either forward or backward into nearly horizontal positions. This enables the rolls to be swung down when the machine is not in use, thus reducing the 95 height of the machine and enabling it to fit in an ordinary cover, or to occupy an ordinary typewriter desk, into the body of which it may slide when the cover of said desk is pulled into horizontal position. In 100 order to permit this, the side pieces 30 and 31 are journaled on the shaft 29, which shaft in turn is journaled in brackets 159.

The brackets 159 are formed as turned-up 105 extensions of a plate 160 which extends between them, thus giving rigidity to the structure. Fast to the right-hand bracket 159 is an extension collar 161, on which the side piece 31 is journaled instead of directly on the shaft 29. This collar 161 is circular 110 except at a point near the bottom but slightly in front of the bottom, at which point a hollow 162 (Figure 4) is cut into it, which hollow is adapted to fit a detent roller 163, said roller being journaled very loosely in 115 openings 164, formed in the downward extension 165 of the side wall 31 and also in the upturned extension 166 of said wall, which is spaced therefrom and lies against the end of the collar 161. The roller 163 120 is pressed strongly against the collar 161 by a broad flat spring 167, which throws the roller 163 into the hollow 162, when the roll frame is in the proper operating position. The frame, however, may be swung from 125 said position by pressure of the hand, thus forcing the roller 163 to ride out of its hollow and ride on the circular face of the collar 161.

Variations may be resorted to within the 130

scope of the invention, and portions of the improvements may be used without others.

Having thus described my invention, I claim:

5. 1. In a typewriting machine, the combination, in a roll-holding device, of a roll core or web-carrying spool, a spindle therefor adapted to pass through the roll core, a slot in said spindle, a spring, a latch adapted to 10 be pressed by said spring to enter said slot, and means giving said latch a limited throw, said spindle having a pointed end adapted to thrust aside said latch when the spindle is inserted to make the spring effective to 15 draw the latch into the slot when the spindle is positioned.

2. In a typewriting machine, the combination, in a roll-holder, of a removable spindle, a roll core or spool having a cut-away 20 end portion, a roll end plate adapted to be journaled on said spindle, a projection on said end plate adapted to enter partway into a roll by reason of the cut-away portion of said roll core, and another end plate to bear 25 against the uncut-away part of said roll core.

3. In a typewriting machine, the combination, in a roll-holder, of a roll core or spool having a portion of the core cut away 30 at one end, a spindle having a handle fast thereto, adapted to be inserted through the roll and roll core, a separate end plate, comprising a hub or bushing adapted to catch in the cut-away portion of the core of the roll, an 35 uncut-away portion of said core adapted to be engaged by the end plate, and a detent on said end plate adapted to engage said spindle to cause the handle to rotate the end plate and thereby rotate the core.

40. 4. In a typewriting machine, the combination, in a roll-holder, of a roll core or spool having a portion of the core cut away at one end, a spindle having a handle fast thereto, adapted to be inserted through the 45 roll and roll core, a separate end plate, comprising a hub or bushing adapted to catch in the cut-away portion of the core of the roll, an uncut-away portion of said core adapted to be engaged by the end plate, a 50 detent on said end plate adapted to engage said spindle to cause the handle to rotate the end plate and thereby rotate the core, an end plate for the opposite end of the roll, and a spring bearing against said latter end 55 plate adapted to thrust the roll and roll core against the other end plate.

5. In a typewriting machine, the combination, in a roll-holder adapted to hold two rolls, of spindles for said rolls, diversely- 60 formed cores for said rolls, each core having its two ends differently formed, an end plate adapted to fit one end only of its own core and having a part projecting too far to fit in the roll-holder when fitted to the other 65 core, and an end plate adapted to fit one end

only of the other core and having a projecting part of incorrect diameter to fit in the roll-holder when fitted to the first core.

6. In a typewriting machine, the combination of a frame, spindles mounted in said frame, a tally-sheet roller on one spindle, a carbon-sheet roller on a second spindle, said rollers each having a cut-away portion at one end, and an end plate mounted on each spindle, each of said plates having a 70 bushing adapted to fit into the cut-away portion of only the corresponding roller, the bushings not being interchangeable for use with the other roller.

7. In a typewriting machine, the combination of a frame, a spindle mounted in said frame, a roller mounted on said spindle and having a cut-away portion at one end surrounding the spindle and having also recesses in its end, and an end plate having 80 a bushing adapted to fit in said cut-away portion, and having also fingers adapted to project into said recesses.

8. In a typewriting machine, the combination of a frame, a spindle mounted in said frame, a web-carrying roller on the spindle, said spindle having a circumferential slot around one end, said end being adapted to project through the frame, and a spring-pressed latch co-operating with said slot to 90 lock the spindle in position, for removably holding the roller on the frame.

9. In a typewriting machine, the combination of a frame, a spindle mounted in said frame and one end of the spindle projecting 100 therethrough, a web-carrying roller on the spindle, a bushing extending through the frame, and through which the end of the spindle passes, and a latch movable on said bushing, said spindle having a circumferential slot around the end of the spindle passing through the bushing, said latch co-operating with said slot to lock the spindle in position, for removably holding the roller 105 on the frame.

10. In a typewriting machine, the combination of a frame, a spindle mounted in said frame, and one end of the spindle projecting therethrough, a roller mounted on said spindle, a bushing in the frame, and through 115 which the end of the spindle passes, an end plate attached to the bushing, a spring between said end plate and roller, and a latch movable in said bushing, said spindle having a circumferential slot around the end of the spindle passing through the bushing, said latch co-operating with said slot to lock the spindle in position.

11. In a typewriting machine, the combination of a frame, a spindle mounted in 125 said frame and having a slotted portion at one end, a roller having a cut-away portion at the same end as the slot, and an end plate mounted on said spindle and having a bushing fitting said cut-away portion, said end 130

plate having also a spring-pressed detent co-operating with said slot to lock the end plate to the spindle.

12. In a typewriting machine, the combination of a frame, a spindle mounted in said frame and having a handle at its end projecting therethrough, said spindle having a longitudinal slot on its surface near one end, a roller having a cut-away portion at the same end as the slot, an end plate mounted on said spindle and provided with a bushing extending in one direction and adapted to fit said cut-away portion, and provided also with a hub extending in the opposite direction and surrounding said spindle, and a spring-pressed detent passing through said hub and co-operating with the slot in said spindle to lock the spindle to the end plate.
13. In a typewriting machine, the combination, in a roll-holder adapted to hold two rolls, of diversely-formed cores for said rolls, a spindle for each core, each core having its two ends differently formed, an end plate adapted to fit one end only of its own core and not adapted to fit in the roll-holder when fitted to the other core, and an end plate adapted to fit one end only of the other core and not adapted to fit in the roll-holder when fitted to the first-mentioned core.

14. In a device for holding a rolled strip

or web on a typewriting machine, the combination of a frame for said device, a web-carrying spool removably mounted on the frame, end plates forming flanges for the spool and from which the spool may be separated, and means to compel the spool to be inserted between the end plates with its ends turned in the right direction.

15. In a device for holding a plurality of rolled strips or webs on a typewriting machine, the combination of a frame for said device, a plurality of web-carrying spools removably mounted on the frame, end plates forming flanges for the spools and from which the spools may be separated, and means to compel each spool to be inserted between its own end plates.

16. In a device for holding a plurality of rolled strips or webs on a typewriting machine, the combination of a frame for said device, a plurality of web-carrying spools removably mounted on the frame, end plates forming flanges for the spools and from which the spools may be separated, and means to compel each spool to be inserted between its own end plates and with its ends turned in the right direction.

ALFRED G. F. KUROWSKI.
